Primary Examiner—Cathy Anne MacCormac

(57) **CLAIM**

I claim the ornamental design for the toy ball with strands for pets, as shown.

DESCRIPTION

FIG. 1 is a perspective view of the toy showing my design;

FIG. 2 is a top plan view thereof, the bottom plan view being a mirror image; and,

FIG. 3 is a right side view thereof, the left side, front and rear are substantially identical.

1 Claim, 1 Drawing Sheet

FIG. 1

FIG. 2

FIG. 3
